UNITED STATES PATENT OFFICE.

WILLIAM S. TOTHILL, OF CHICAGO, ILLINOIS.

SWING.

SPECIFICATION forming part of Letters Patent No. 231,942, dated September 7, 1880.

Application filed November 4, 1879.

To all whom it may concern:

Be it known that I, WILLIAM S. TOTHILL, of Chicago, Cook county, State of Illinois, have invented a new and useful Improvement in 5 Swings, (Case A,) of which the following is a full description, reference being had to the accompanying drawings, in which—

Figure 1 is a front elevation; Fig. 2, a vertical cross-section; Fig. 3, a side elevation of 10 the seat or chair enlarged, and Fig. 4 a front view of the same. Figs. 3 and 4 also show a modification of the seat-supports.

The object of this invention is to improve 15 the construction and operation of the swing patented to me July 30, 1878, No. 206,406; and its nature consists in an improved method of attaching the operating-cord and the arm, and in the construction, attachment, and operation of the seat, as hereinafter described.

20 In the drawings, A indicates an ordinary door frame or casing; B, the swinging bars; C, a pivoted yoke or bar for connecting the operating-cord; D, a projecting bar or bracket attached to the top of the frame; E, the seat or chair; a, the operating-cord; b, the point of 25 attachment; c, a sheave or pin; e, cord or cords for holding the yoke C; f, rear posts of the seat; g, front posts; h, seat; i, base-rails; i', foot-board; j j', cords or hook for holding the seat, back, front, and foot-board in position; l, pivots of the rear and front posts of the chair, and 30 k k' pins for adjusting the pitch of the chair back and front when the cord j is used.

The supporting-frame is an ordinary door 35 frame or casing upon which the swinging bars B are hung, and upon which the projecting bar or bracket D is supported, making a complete support for the swing for indoor use. For out-of-door use a separate framing is made 40 to take the place of the door casing or frame by similarly connecting the swinging bars and the bar or bracket D thereto.

The bars B are made by splitting a single piece with a saw or otherwise into two parts, 45 B B', or in other suitable manner.

The posts B B' are held apart by cross-bars, as shown, and at a suitable distance above their lower ends the seat h is attached. To this 50 seat or to its supports the back and front of the seat are pivoted, forming a chair. At the lower ends of the posts f and g the bars i are

also pivoted, so that whenever the back is tilted either up or down the bars i and the foot-rest i' will maintain their relatively-horizontal position as they move up and down. 55

When in the position shown the back, seat, front, and foot-rest assume the form of a chair; but when the cord j or ratchet j' is released these several parts come nearly or quite into line, so as to form a bed or cradle. 60

The device is supported in intermediate positions by the cord j and a series of pins, k k', or by the ratchet-notches. This seat or chair may also be supported by the parts B B' from the floor, so as to be separately used. 65

The yoke or bar C is pivoted to the bars B when in yoke or bow form, and to one of them when in bar or rod form, and is held in position for use by the cord or cords e, which cord permits of the folding down of the yoke for 70 storage or other purpose. The cord a is attached to this yoke at b, carried up and around the sheave or pin c, and extended down so as to be within convenient reach of the occupant of the chair. 75

By extending out the bar or bracket D over, or nearly over, the yoke or bar C, the power applied to the cord has a much greater effect in moving the swing than when the sheave c is near to or at the line of the pivots of the bars 80 B; and by the arrangement of the bar i and foot-board or bars i' they are at all times horizontal whatever the position of the front and back may be.

What I claim as new, and desire to set 85 cure by Letters Patent, is—

1. The combination of the sheave or pulley c, horizontally-projecting bracket D, and cord a with the projecting yoke or bar C and the swinging bars B, the cord a being attached to 90 the yoke and passing over the pulley, whereby a direct leverage on the swinging bars is obtained, substantially as specified.

2. The pivoted yoke or bar C, in combination with the swinging bars B, and the cord or 95 cords e, cord a, attached to said yoke, bracket D, and pulley c, whereby the yoke is held firmly against the pull of the operating-cord and free to be folded down without detaching any of the parts fastened thereto, substantially as described. 100

3. The seat h, attached to the supports B

B', in combination with the pivoted posts *f* *g*, pivoted bars *i*, foot-rests *i'*, and means for adjusting the position of the movable parts, all constructed and operating substantially as specified.

4. The combination of the base rails or bars *i* and foot-board *i'* with the posts *f* and *g*, extended below the seat-pivot and seat *h* and

attached to the base-rails *i*, whereby the foot-board *i'* is maintained in a horizontal position, substantially as specified.

WILLIAM S. TOTHILL.
